DISPENSING PUMP FOR CONTAINERS

Edwin Arthur Speaker, Wheeling, W. Va., assignor to
Continental Can Company, Inc., New York, N.Y., a
corporation of New York

Application March 19, 1959, Serial No. 55,054

Term of patent 14 years

(Cl. D62—2)

Figure 1 is a perspective view illustrating a dispensing pump for containers embodying my new design.

Figure 2 is a top plan view thereof.

Figure 3 is a side elevational view thereof with a part of the lower portion broken away for convenience of illustration only.

Figure 4 is a bottom plan view thereof.

The side of the dispensing pump for containers opposite that shown in Figure 1 is a mirror image of the side shown.

I claim:

The ornamental design for a dispensing pump for containers, as shown and described.
